(57) **CLAIM**

The ornamental design for a biological information measuring device, as shown and described.

DESCRIPTION

FIG. 1 is a perspective view of the biological information measuring device showing my new design;

FIG. 2 is a top view of the biological information measuring device showing my new design;

FIG. 3 is a bottom view of the biological information measuring device showing my new design;

FIG. 4 is a left side view of the biological information measuring device showing my new design;

FIG. 5 is a right side view of the biological information measuring device showing my new design;

FIG. 6 is a rear view of the biological information measuring device showing my new design; and,

FIG. 7 is a front view of the biological information measuring device showing my new design.

The broken lines depict portions of the biological information measuring device that form no part of the claimed design.
